UNITED STATES PATENT OFFICE

HARRY WOLF, OF CHICAGO, ILLINOIS, ASSIGNOR TO CUTTER-CROSSETTE COMPANY, OF CHICAGO, ILLINOIS, A CORPORATION OF ILLINOIS

NECKTIE

Application filed December 28, 1928. Serial No. 328,899.

This invention relates to improvements in neckties of the four-in-hand type and methods of making the same and has for its main object to produce a necktie wherein the outer fabric, such as bias cut silk, is so associated with lining material as to render the outer fabric and lining each cooperative with the other to prevent distortion of the materials by the strains and stresses imposed thereon and cause each of the two materials to cooperate with the other to effect a self-recovery of the tie from the creased or rumpled state in which it is usually found upon removal from the collar. 5 A further object of the invention is to provide a necktie wherein the lining is so associated with and distributed over the outer fabric as to give more body to the tie without rendering the same bunched in spots while causing a very graceful folding or creasing of the same at and adjacent to the knot portion when tied. 10

As to the method comprehended within the invention as distinguished from the article, the main object of the invention resides in first associating a piece of lining of an area sufficient for an appreciable number of ties with an equally large piece of outer fabric and thereafter cutting the associated lining and fabric into blanks of size and shape required for the assembly of the latter into completed ties. 15

The invention is illustrated in the accompanying drawings wherein:

Fig. 1 is a plan view showing a piece of fabric such as is customarily used for the outer or visible portion of a tie and a piece of lining material of a suitable type secured thereto. 20

Fig. 2 is a plan view of a blank for the production of a tie cut from the associated fabrics shown in Fig. 1.

Fig. 3 is a plan view showing the two pieces cut from the blank of Fig. 2 associated and the edge portions of the outer fabric hemmed preparatory to completing the tie. 25

Fig. 4 is an enlarged transverse sectional view on the line 4—4 of Fig. 3.

Fig. 5 is a rear elevation of a completed tie

constructed in accordance with this invention.

Fig. 6 is an enlarged transverse sectional view on the line 6—6 of Fig. 5.

Figs. 7 and 8 are views similar to Fig. 3 illustrating other or modified embodiments of the invention.

Fig. 9 is a transverse section on the line 9—9 of Fig. 8, assuming the latter to be in finished condition as exemplified in Fig. 5 as to the structure of Figs. 1 to 6, inclusive. 50

In the manufacture of neckties in accordance with the present invention, I employ the conventional type of outer fabric which is furnished in certain lengths by the mills, each piece being bias-cut at its ends in order to obviate waste. 55

Lining material of a suitable character, such as loosely woven wool fabric, is purchased by the bolt and bias-cut into pieces corresponding in length with the outer fabric pieces or cover fabrics or casings of neckties, the lining material being of less width than the outer fabric material. 60

Thus a piece of the lining material 1 is laid upon the reverse or back-face of the piece 2 of outer fabric material, which I shall hereafter term "silk", so that the side or self-edges of both pieces 1 and 2 are parallel and the piece 1 is disposed substantially midway between the side edges of the silk 2. 65

The pieces 1 and 2 are now secured together in any suitable manner but I have to date found no means other than blind-stitching to be satisfactory and, consequently, I prefer to employ a gang-needle blind-stitching machine to join the pieces 1 and 2 which serves to attach the lining without rendering the stitches 3 visible from the outer or visible face of the completed tie. 70

The associated pieces 1 and 2 are now cut into the conventional type of necktie blanks 4 such as is shown in Fig. 2 and this blank is then cut along the dotted line 5 to produce the two blanks 6 and 7 of Fig. 3 which are then attached by stitching together by the line of stitching 8. 75

The lining elements of the necktie blanks of Fig. 3 are now trimmed away along one side sufficiently to leave an edge portion 9 of

silk only and incisions 10, 11, 12, and 13 cut into the edge portions of the silk, the said incisions permitting the unlined free end portions of the silk to be hemmed as shown.

5 A small portion 14 of the opposite edge of the lining is also cut away to permit the hem of the silk to be extended to produce the usual finish.

10 The portion 9 of the silk is now folded upon itself only and the line 15 of stitching effected and then the blank of Fig. 3 is folded, by the usual sad iron method, along the dotted lines 16 and 17 and the folded portion 9 then joined by suitable stitching 18 to the 15 silk along the opposite edge of the blank though this stitching 18 may extend through the lining edge at this point. This stitching may be effected by means of a blind-stitching machine or in any other suitable manner, 20 attention being directed to the fact that because of the lining being so intimately associated with the silk, these ties cannot be completed or practically completed with the lining disposed on the exterior and then turned 25 as is customarily done in necktie manufacture when the silk structure per se is first completed, then turned and the lining then inserted and secured in place.

It will be obvious that by reason of the 30 necessary bias-cut of the silk, the lining, because of its position on the silk, is also bias-cut but no appreciable advantage other than economy of material results from thus cutting the lining. In the structure of this 35 application the lining is intended and adapted to prevent stretching of the silk longitudinally of the completed tie to any greater extent than the lining because practice has clearly demonstrated that if the silk is 40 stretched beyond the limit of self-restoring elasticity of the lining it will remain more or less permanently distorted and cannot be restored to normal condition by the lining because the silk is, in every instance known to applicant, far more resilient than the 45 lining unless the latter is also silk cut on the bias.

I have also found in practice that the self-restoring characteristic of the silk is the main 50 factor in the self-restoration of the tie to normal condition since the silk, especially in the above described structure, serves to restore the lining to normal condition.

55 In the above structure, I employ a thinner lining than is ordinarily used because there is no advantage from the standpoint of self-restoration in using a thick lining while the use of the latter would be disadvantageous in rendering the tie too bulky. 60 The thinner lining is also very advantageous in that it will offer less resistance to restoration by the silk than would a thicker or heavier lining.

65 Obviously a lining material which has a tendency toward self-restoration from a

creased and distorted condition is preferable to one devoid of that characteristic since it will offer less resistance to self-restoration of the silk.

The essential characteristic of the tie of my invention consists, therefore, in such an association of the silk and lining as will serve to prevent any relative movement between these parts within the area covered by the lining. As this part of the tie is practically the only part that is subjected to stresses and creases when forming and during the time that the knot of the tie remains, it is unnecessary to extend the lining beyond the area shown.

In Figs. 7, 8, and 9, I have illustrated embodiments of the invention from a purely structural standpoint differing from that shown in Figs. 1 to 6 inclusive, the embodiment of Fig. 7 including the same outer or silk structure to which a lining strip comprising a bias-cut piece 19 in the larger or knot portion is secured by means of blind-stitching as best shown in Fig. 7. This piece 19 is of the width of the said larger end portion of the silk body between the side folds or creases indicated by the reference numerals 16 and 17 in Fig. 3. The length of this piece 19 is such that it extends from the usual terminal point near the free end of the larger portion of the silk body to a point adjacent that at which the larger end or knot portion of the body merges into the neckband or middle portion of said silk body. At the last-named end the piece 19 is stitched to one end portion of the strip 20 of lining which is not bias but is straight cut and extends through the neck-band and into the smaller end portion of the silk body, the strip 20 overlapping the strip 19 for a distance of three or four inches. This composite strip of lining is preferably firmly secured to the silk body by means of a plurality of blind-stitch chains 21 which may be limited to only the bias-cut portion 19. Obviously, the composite lining 19-20 is cut and coupled separately from the cutting and joining the two portions of the silk body.

In this structure only the portion 19 of the lining possesses an appreciable degree of resiliency but the bias-cut of the lining piece 19 is adopted only because it appears to produce a more graceful and attractive knot, the single thickness permitting the use of heavier lining material or reducing the bulk incident to the use of a wider lining such as is shown in Figs. 1 to 6 inclusive.

The structure of Figs. 8 and 9 is more nearly identical with that of Figs. 1 to 6 in that the lining piece 22 for the larger or knot-end portion of the silk structure is of the same width as the similar portion of the lining of Figs. 1 to 6. This piece 22 is also cut separately from the silk and before being mounted on the latter by means of blind-stitching is

creased along its side edge portions and the flanges 23 thus produced are stitched to the middle portion of said lining by means of stitch-chains 24. It will be noted that in the structure of Fig. 8 the blind-stitch chains 25 pass through the middle portion of the piece 22 between the stitch chains 24, the flanges 23 being left free because of the difficulty of securing the same to the opposed 10 portions of the silk body composing the rear wall of the tie. The strip 26 of lining for the neck-band and smaller end portions of the silk body is identical with the strip 20 of Fig. 7 and overlaps the stitched lining piece 22 and its flanges for a distance of three to 15 four inches.

I have found the folding and stitching of the piece 22 of Fig. 8 to be very advantageous as the wool lining material tends to bulge between the stitch-chains 24 and the folded side 20 edges to produce somewhat elliptical tubes which are advantageous in adding to the graceful appearance of the tie when worn.

The overlap of the lining pieces 20 and 26 25 respectively tend to reduce the resiliency of the pieces 19 and 22 respectively, and add to the bulk of the body at the top or inner end of the knot portion. In some instances a loose strip of bias-cut wool lining is added 30 which extends substantially from one end of the tie to the other to add to the bulk of the structure. I prefer to employ a wool or silk lining material because of the greater tendency of these fabrics to self-restoration to initial 35 condition when the tie is not worn, the wool lining being preferred to the silk because it is cheaper.

I claim as my invention:

The method of making neckties which includes the spreading of a piece of lining material over a piece of outer bias cut silk fabric, the side edges of the latter and the lining being substantially parallel, then attaching the lining to the outer fabric over substantially the entire area of the lining, then bias cutting the lined fabric into conventional blanks, then arranging and joining the cut blanks to form a complete tie blank, and thereupon trimming away a side edge portion of the lining to leave a free edge portion of silk to permit hemming and stitching together of opposite side edge portions of the outer fabric free of the said lining, and thereupon completing the tie.

HARRY WOLF.
